UNITED STATES PATENT OFFICE.

GEORGE W. KNIGHT, OF HOPEDALE, MASSACHUSETTS, ASSIGNOR TO
DRAPER COMPANY, OF HOPEDALE, MASSACHUSETTS, A CORPORA-
TION OF MAINE.

RING SPINNING OR TWISTING APPARATUS.

No. 851,812.

Specification of Letters Patent.

Patented April 30, 1907.

Application filed October 3, 1906. Serial No. 337,231.

To all whom it may concern:

Be it known that I, GEORGE W. KNIGHT, a citizen of the United States, residing at Hopedale, county of Worcester, and State of Massachusetts, have invented an Improvement in Ring Spinning or Twisting Apparatus, of which the following description, in connection with the accompanying drawings, is a specification, like letters on the drawings representing like parts.

This invention relates to spinning or twisting apparatus wherein the yarn is led to the rotating spindle through or from a traveler revoluble on a ring, and my invention has for its object the production of novel and efficient means for cushioning the ring with relation to its holder, whereby, under the variations due to unbalanced load, yarn tensions or improper centering of the spindle, slight axial or lateral movement of the ring is permitted and such movement cushioned.

The invention does not belong to the so-called "rotary ring" type of apparatus wherein the essence of the structure is a free rotation of the ring at all times when the apparatus is in motion, but as will hereinafter appear the ring in my present invention may or may not rotate, according to the various exigencies of operation.

The novel features of my invention will be fully described in the subjoined specification and particularly pointed out in the following claims.

Figure 1 is a diametral section on the line 1---1, Fig. 2, of a spinning or twisting ring and cushioned ring-holder embodying one form of my present invention; Fig. 2 is a partial top plan view thereof, the ring and down-hold being broken out to show the ring seat and the cushioning means; Fig. 3 is a detail enlarged, in side elevation of the ring-holder and ring; and Fig. 4 is a diametral section thereof similar to Fig. 1 but much enlarged.

I have herein shown the ring as of a well known type, having upper and lower circular flanges 1, 2, connected by a cylindrical web 3, and technically termed as a double-flanged ring, the uppermost flange serving in usual manner as a raceway for the traveler.

In the present embodiment of my invention I have shown the ring-holder as comprising a cylindrical or tubular body 4 having a laterally extended circular head 5 which

rests upon the ring-rail R, see Fig. 1, the body 4 depending through the usual hole in the rail, the spindle, (not shown) passing up through the body of the holder.

The ring-holder is provided with an annular ring-seat 6 having an outer circular side wall 7, and the top of the head 5 is also provided with a shallow and concentric seat or recess 8. The ring-seat has pressed or inserted in it a cushion or lining 9 of suitable non-metallic material, such as thin leather, rubber, etc., which will serve as a cushion for the ring, such lining or cushion covering the seat and being upturned against the side wall 7, as clearly shown at 10 in Figs. 1 and 4, and partly in Fig. 2.

Within the lined or cushioned seat the lower flange 2 of the ring is inserted, not with a tight and immovable fit, but with sufficient ease or looseness to permit slight axial and radial movement of the ring, and at times even some rotative movement. It will be manifest that the bottom of the ring is cushioned, and also the edge or periphery of the base flange, thereby preventing any shock or jar to the ring when it is moved either axially or vertically.

The ring-holder has a down-hold to limit vertical ring movement, and herein the down-hold is shown as two semi-circular metallic segments 11, held in place by screws 12 or other fastenings passed through the head 5 and into the segments.

A thin washer-like cushion 13 of leather or other suitable material is laid in the recess 8 and its inner portion extends over and above the flange 2 of the ring, as shown, the down-hold retaining said ring-like cushion in place, and thereby cushioning the top of the flange when the ring is lifted.

As shown in Figs. 1 and 4 the inner edge of the down-hold extends far enough over the ring flange to retain the ring on the holder, the fastenings 12 in practice passing through holes made in the cushion 13.

By the construction herein shown and described the ring is securely retained in position on the ring-holder, yet it is effectually cushioned against any shock or jar which would result from the metal surface of the ring striking against any metallic surface on the ring-holder. I am, by cushioning the ring, enabled to secure a very smooth action,

free from all jar or shock, when the apparatus is in use, resulting in better spinning or twisting of the yarn, and reducing yarn breakage.

5 Having fully described my invention, what I claim as new and desire to secure by Letters Patent is:—

1. A ring-holder having an annular seat, a non-metallic lining for and resting against the bottom and outer wall of the seat, and a ring having a flange supported on the lining and vertically and laterally cushioned thereby.
- 10 2. The combination, with a ring-holder

having an annular seat and a downhold, a continuous cushion lining the bottom and side wall of the seat, a ring having a flange loosely resting in the cushioned seat, and a cushion overhanging the seat and interposed between the downhold and the top of the ring flange.

In testimony whereof I have signed my name to this specification, in the presence of two subscribing witnesses.

GEORGE W. KNIGHT
